PASTE-APPLYING DEVICE

William S. Cleaves, Wollaston, Mass.

Application May 19, 1933, Serial No. 671,860

2 Claims. (Cl. 15—209)

This invention relates to a paste-applying device particularly useful in the application of shoe polish, to a unitary package for use in the paste-applying device, and to a method of dispensing and applying a paste such as a shoe polish.

One object of the invention is to provide a novel and efficient device for use in the application of a paste such as shoe polish, to enable such operation to be performed in a more economical, efficient and convenient manner than has heretofore been possible.

A further and more specific object of the invention is to provide a novel device for applying a paste such as a shoe polish, which is provided with a handle and with a body of paste enclosed within a perforate compressible non-metallic container detachably secured to the handle to form a unit therewith.

Another object of the invention is to provide a novel unitary package capable of use with a holder, and in some instances of use by itself in applying a paste such as a shoe polish, and which is characterized by a perforate compressible non-metallic container, preferably a fabric container, enclosing a body of paste and with the consistency of the paste related to the perforations in the container whereby the paste is caused to exude through the same when the container is wiped across the surface to which it is desired to apply the paste.

Another object of the invention is to provide a method of dispensing and applying a paste such as shoe polish to objects such as shoes, and by which economies in both the time consumed in the application of the paste as well as in the amount of paste used, together with an efficient distribution of the paste to the object, may be accomplished.

With these objects in view and such others as may hereinafter appear, the invention consists in the paste-applying device, in the method of dispensing and applying paste, and in the various structures, arrangements, and combinations of parts hereinafter described and particularly defined in the claims at the end of this specification.

In the drawing illustrating the preferred embodiments of the invention, Fig. 1 illustrates a plan view of a cylinder of the paste upon a sheet of gauze and prior to enclosing the paste within the gauze; Fig. 2 is a side elevation of the same; Fig. 3 is a vertical sectional view illustrating an intermediate step in the formation of the completely enclosed paste; Fig. 4 is a side elevation of a cylinder of the paste; Fig. 4a is a side ele-

vation of the completely enclosed paste; Fig. 5 is a plan of the handle forming a part of the present paste-applying device; Fig. 6 is a cross-sectional view taken on the line 6—6 of Fig. 5; Figs. 7 and 8 are views in side elevation of the completely assembled paste-applying device, Fig. 7 being shown with a portion of the cover member broken away and Fig. 8 with the cover member removed; Figs. 9 and 10 are plan and side elevation, respectively, of the cover member; and Fig. 11 is a sectional detail of an alternate form of holder for use with the present package.

Referring now to the drawing which illustrates the preferred embodiments of the invention, the present paste-applying device includes a body 1 of paste, preferably preformed into cake form, as shown in Fig. 1. The body 1 of paste is enclosed within a perforate compressible container 2 comprising preferably an open mesh fabric. The fabric is preferably wrapped about the cake 20 to form a bag-like container 4, and thereafter the latter may be gathered at the neck and bound with a binding member 3. The device further includes a holder, preferably a handle 5 having an opening 6 at one end thereof, and is herein shown as provided with a fastening device 8 secured to the handle by means of pins 9. In order to operatively position the container 4 on the handle, the neck portion 7 of the bag may be extended through the opening 6 and detachably fastened to the handle by means of a fastening device 8. As herein shown, the fastening device 8 comprises a hooked metal member under which the projecting mouth or neck portion of the bag-like container 4 may be hooked to detachably retain the container 4 in operative position upon the handle, as shown in Fig. 8. In order to facilitate packing of the paste-applying device in a travelling bag and also to protect the container 4 when the device is not in use, a protective cover 10 comprising preferably a cylindrical metal member provided with screw threads 11 on its open end is arranged to screw upon a threaded base portion 12 secured to the handle in concentric relation to the opening 6, thus forming a protective cover for the container 4 and preventing contact of the paste with wearing apparel within the travelling bag. The cylindrical cover 10 is provided with a knurled band 13 to aid the consumer in removing the cover 50 from the handle. The cover 10 also may serve to prevent the paste from becoming hardened and dried from excessive exposure.

In practice I prefer to use an open mesh fabric for wrapping shoe paste or polish of the ordinary

consistency now used, and in which the perforations lie within the range of sizes of the perforations in a woven cotton gauze of from 34 to 54 picks per inch. Perforations of this size have been found suitable for use with paste of the ordinary consistency now employed for polishing shoes, in order to effect the most efficient application of the correct amount of paste by a wiping operation across the surface of the shoe. It is to be understood, however, that the sizes of the perforations may be varied in accordance with the consistency of the particular paste being used.

Heretofore, shoe polishes have been sold in round shell boxes with tight covers that are difficult to remove and replace and the polish has usually been applied either by a dauber made of felt or similar material which, owing to the usual composition of the polish, soon dries out and hardens so as to render it useless, or by means of a piece of cloth. The latter method invariably soils and stains the hands of the user.

In the use of the invention, the present pre-formed package containing polish of any desired color may be removed from the container in which it is dispensed, and may be attached to the handle by drawing the neck of the bag through the opening provided therein and by securing the projecting neck of the bag by means of the fastening device 8. As the bag is rubbed over the surface of the shoe the polish contained therein exudes through the open mesh fabric in a thin even coating. When the unit has become exhausted or when it is desired to use polish of another color, the container 4 may readily be detached from the handle and replaced by another.

It is contemplated that these paste-containing units may be dispensed in metal or other suitable containers having press top covers which are easily removable. Each box may contain units of all one color or in varied colors, as the consumer may desire.

An important advantage resulting from the arrangement of paste-applying device illustrated herein resides in the ability to draw the bag-like container up through the holder in the handle to compensate for the paste as it is used, and in this manner it is possible to maintain the fabric drawn tightly across the surface of the paste.

In Fig. 11, I have illustrated a modified form of the present paste-applying device, including a fabric container enclosing a body of polish, and a flexible holder 32 to which the fabric container is detachably secured. The flexible holder 32 comprises preferably a rubber cup-shaped holder having a central opening and enlarged portions

forming a knob or handle 37 and the neck of the fabric bag or container may be drawn up through the opening to permit the resiliency of the rubber to detachably clamp the bag to the holder. From time to time during the use of the device, the operator may draw up the neck of the bag to maintain the polish in a compact mass within the bag, thus enabling all of the polish to be used.

As used throughout the claims, the term "ball-like" is intended to include those various forms of substantial dimensions in all directions, such as spherical, cylindrical, cubical, and the like, and the ball-like form of the body of shoe paste enables the paste to be applied to all of the different portions of the shoe when worn with minimum liability of the application of the paste to the stocking.

While the preferred embodiments of the invention have been herein illustrated and described, it will be understood that the invention may be embodied in other forms within the scope of the following claims.

Having thus described the invention, what is claimed is:

1. In a shoe dauber, the combination with a handle, of a shoe paste cartridge comprising a small fabric bag entirely enclosing a unitary ball-like cartridge of shoe paste, the upper portion of the bag being closed, the upper portion of the bag being arranged to project in effect as a fabric neck or handle by which the cartridge may be handled with minimum liability of soiling the hands during its attachment to the handle of the shoe dauber, the bag formed of a material such as to permit paste to exude therethrough, when the bag is pressed lightly against the shoe, said handle having provision, including means to detachably secure said neck to said handle, whereby the slack in the body of the bag may be taken up from time to time to maintain the cartridge in ball-like form.

2. In a paste dauber, the combination with a handle, of a paste cartridge comprising a small fabric bag entirely enclosing a unitary ball-like cartridge of paste, the upper portion of the bag being arranged to project in effect as a fabric neck or handle by which the cartridge may be handled with a minimum of liability of soiling the hands during its attachment to the handle of the dauber, said handle being formed of elastic rubber-like material and having an aperture for insertion of the neck of said bag for frictionally and resiliently gripping said neck, whereby the slack in the body of the bag may be taken up from time to time.

WILLIAM S. CLEAVES.
